UNITED STATES PATENT OFFICE.

HARVEY A. MOYER, OF SYRACUSE, NEW YORK.

CORNER-IRON FOR CARRIAGE-SEATS.

SPECIFICATION forming part of Letters Patent No. 293,663, dated February 19, 1884.

Application filed May 7, 1883. (No model.)

To all whom it may concern:

Be it known that I, HARVEY A. MOYER, of Syracuse, county of Onondaga, and State of New York, have invented new and useful Improvements in Seat Corner-Irons for Wagons, Buggies, &c.; and I do hereby declare that the following is a full, clear, and exact description of the same, reference being had to the accompanying drawings, and to the letters of reference marked thereon.

This invention consists, mainly, in constructing a seat-iron of a flat metallic strip of L-shaped form, with short ribs adapted to furnish the proper metal for fastening purposes without coming in contact with the seat-cushion.

It consists, further, in the combination, with the main corner-iron, of an auxiliary corner-iron of specific construction, located at the junction of the base-board with the side-board of the seat, at the front edge of the same.

In the drawings, Figure 1 represents a perspective view of one end of a wagon-seat, having my improved iron applied thereto; Fig. 2, a top view of the main corner-iron detached; Fig. 3, views of the auxiliary corner-irons detached, and Figs. 4 and 5 perspective views of the seat corner-irons constructed with a shifting-rail.

A represents the seat, having the horizontal base-board a , of any proper construction, the inclined back-board a' , and the inclined side-board a'' , as shown. The back-board a' and the side-board a'' are united to the base-board a at their lower edges in any proper manner, and these two are themselves secured together at the corner by any proper fastening devices.

B represents the main corner-iron, consisting of a flat metallic strip of L-shaped form, the short arm b of which is adapted to cover the upper edge of the back-board a' for a proper distance near the corner of the same, and the long arm b' of which is adapted to cover the edge of the side-board a'' throughout its entire extent, and also to project over the same both at the point b^2 , at the front edge, and along the entire side, as indicated in dotted lines, Fig. 1. This iron, it will be observed, is provided with a series of openings, by means of which it may be strongly screwed to the edges of the back-board and side-board, as shown in Fig. 1.

b^3 b^4 represent ribs, located upon the upper face of the irons, which are provided with proper openings, as shown, for the irons of the shifting-rail, and also with projecting portions b^4 , adapted to extend a short distance down the back and side boards, as shown.

b^5 represents a boss, having an opening for one of the irons of the shifting-rail, which boss may be provided with a rib, b^6 , with projection b^7 , if desired. This iron is strongly secured to the upper edges of the back and side boards by screws, as shown. The projections b^4 are also properly secured by screws, as shown.

C represents the auxiliary corner-iron, consisting of a metallic strip having two nearly-equal arms bent at an obtuse angle, and provided at the angle with a right-angled projection, c , as shown. This iron is strongly secured to the front edge of the base-board a and side-board a'' , at the junction of the same, by means of screws, as shown. The projection c , it will be observed, overhangs the inner surface of the base-board and the side-board at the joint. By means of the series of screw-openings in connection with the ribs b^3 b^4 the iron is strongly secured to the edges of the seat.

By means of the short ribs b^3 b^4 the proper metal is furnished for fastening purposes without coming in contact with the cushion and subjecting the same to wear.

By means of the auxiliary corner-iron the main corner-iron is strongly re-enforced at its weakest point. By means of the projection c the strength of this auxiliary corner-iron is very greatly increased.

Having thus fully described my invention, what I claim as new, and desire to secure by Letters Patent, is—

1. The flat metallic strip B, of L-shaped form, having the series of screw-openings, and the ribs b^3 , with short extensions, as and for the purpose described.

2. In combination with the main corner-iron, the auxiliary corner-iron having the overhanging portion c , as described.

This specification signed and witnessed this 3d day of April, 1883.

HARVEY A. MOYER.
